(57) **CLAIM**

The ornamental design for a food container for chicken, as shown, and described.

DESCRIPTION

FIG. 1 is a perspective view of a food container for chicken showing my new design with the lid open;
FIG. 2 is a perspective view thereof with the lid down;
FIG. 3 is a top plan view thereof in an unassembled condition;
FIG. 4 is a side view thereof with the lid open as shown in FIG. 1, with the opposite side view being a mirror image thereto;
FIG. 5 is a front view thereof;
FIG. 6 is a rear view thereof; and,
FIG. 7 is a bottom plan view thereof in an unassembled condition.

1 Claim, 4 Drawing Sheets

FIG. 3

FIG. 7
